UNITED STATES PATENT OFFICE.

ISAAC I. LANCASTER AND HOMER A. SEARS, OF GOLDENDALE, WASHINGTON TERRITORY.

SADDLE-GIRTH FASTENING AND HARNESS-BUCKLE.

SPECIFICATION forming part of Letters Patent No. 244,624, dated July 19, 1881.

Application filed May 13, 1881. (Model.)

To all whom it may concern:

Be it known that we, ISAAC I. LANCASTER and HOMER A. SEARS, of Goldendale, in the county of Klickitat, Washington Territory, have 5 invented a new and useful Improvement in Saddle-Girth Fastenings, of which the following is a full, clear, and exact description.

Our invention relates to means for securing and tightening saddle-girths, to be used in 10 stead of buckles.

The invention consists in a novel construction of a plate and a pair of pivoted spring-pawls, and a novel construction of the girth, and certain details connected therewith, where- 15 by provision is made for securely and quickly tightening or loosening the girth, as hereinafter described.

In the accompanying drawings, Figure 1 is a general view of devices embracing our im- 20 provements. Fig. 2 is a longitudinal section taken in the line $\alpha\alpha$ of Fig. 1. Fig. 3 is a detail view of one of the pawls.

Similar letters of reference indicate corresponding parts.

25 A represents a portion of a saddle-girth of the usual description, except that its end is extended into or provided with a strap or tongue, B, which is much longer than the strap or tongue usually employed at the end of the 30 girth, and is provided with notches *b* on both edges.

C represents a ring or link, consisting of a round bar bent to form somewhat more than a half-circle, and having its ends connected by 35 a roller, D.

E are two straps, having their lower ends attached to the ring or link C, and their upper ends attached to the saddle-tree.

G is a metallic plate, riveted or otherwise 40 attached to the girth A, and H is a plate riveted or bolted to the plate G. Between these two plates, near one end, are secured two longitudinal bars, J J, the outer ends of which are turned outward beyond the plate H and 45 formed into lugs, which serve as bearings for a roller, K, while the main portions of the bars, being parallel with each other, serve to guide the strap or tongue B, as hereinafter described.

Near the other end, between the plates and in line with the bars J J, are two similar bars, 50 J² J², minus the lugs and roller.

At two opposite edges of the plate H, and extending outward beyond the bars J² J², in opposite directions, are two lugs, h h, in which are pivoted two pawls, L L, with their noses 55 pointing inward toward each other and working between the contiguous ends of the bars J and J².

If desired, the bars J and J² may be in one piece, and provided with a slot for the nose of 60 the pawl to work in. Each pawl is provided with a spring, l, which bears against the bar J² with a tendency to press the outer end of the pawl outward and the nose inward.

The operation of the invention is as follows: 65 The strap or tongue B is passed up through the link C, then down around the roller D, and then between the plates G and H and bars J and J², and under the roller K. When the strap is pulled the girth is tightened, and the 70 strap is held in position by the engagement of the pawls L with the notches *b*. By pressing the upper ends of the pawls toward each other their noses are withdrawn from the notches, and the tongue B may be loosened or entirely 75 drawn out.

Having thus described our invention, we claim as new, and desire to secure by Letters Patent—

1. In a saddle-girth fastening, a strap or 80 tongue, B, having its edges provided with abutments or notches *b*, in combination with pawls L, arranged and operating as herein shown and described.

2. The combination, with a saddle-girth, A, 85 and tongue or strap B, of the plates G H, pawls L, bars J J², and roller K, substantially as and for the purpose herein described.

3. The pawl L and spring l, in combination with the plates G H, lugs h, and bars J², as 90 herein shown and described.

ISAAC INGERSOL LANCASTER.
HOMER ALDEN SEARS.
